SOSTHÈNE HENRI LIBER, OF PARIS, FRANCE

ELECTRIC CONTROLLING DEVICE

Application filed July 26, 1929, Serial No. 381,377, and in France January 29, 1929.

Filing devices are in use in which the set of filing cases forms a movable carriage which may travel in both directions upon rails mounted on a stationary frame. The said carriage may thus present before the operator's stationary outfit the various filing cases which it contains. Inversely, it has been proposed to mount the operator's outfit upon rails so that it will be movable before the filing device, which is now in the fixed position. In these cases the filing device and the operator's outfit may thus be given alternate relative movements.

The present invention relates to a controlling arrangement for the obtainment of such relative displacements, and for the control of their direction and extent, by electric means. For this purpose, the electric motor, which by means of a suitable driving device may effect the displacement of one of the movable apparatus, has its circuit controlled by a double switch for reversing and breaking the circuit. The circuit is further controlled by switches adapted to stop the motor if for any reason the circuit has not been broken when the movable apparatus attains the end of its travel.

In the accompanying drawings and by way of example:

Fig. 1 is a diagram of the electric circuits.

Fig. 2 shows the reversing switch partly in vertical section and partly in elevation, with the cover removed.

Fig. 3 shows one of the switches used at the end of the travel partly in vertical section and partly in elevation, with the cover removed.

The apparatus controlling the circuit will be first described before indicating their connections.

A.—Switching device.—The said device comprises two pivoted contact elements 1—2. Said elements consist each of a sealed glass tube of curved shape carrying upon its convex part projections 4—5—6 or 4'—5'—6' to which are attached conducting wires. One projection is midway between the two others. The said tube contains mercury. The volume of the mercury is such that it may connect the wires of either end projection with the central projection when the tube is tilted.

These circuits are broken when the tube is brought into the position in which the middle projection is vertical.

Each of said tubes is mounted on a strap 7 secured to bosses 8 laterally projecting at the lower part of each vertical face of a controlling knob. The horizontal axle 10' of the angular displacements of said knob 9 is mounted in two parallel cheeks 10 which cross-connect the two sides 11 and the top 12 of the casing containing the mechanism. The top 12 forms a flat base, and it is apertured at 13 for the insertion of a part of the lateral surface of the knob 9. This part is suitably faced in such manner that it may be controlled. On the sides 11 of the casing are mounted the electric terminals to be connected in the circuit.

In the upper part of the knob or disk 9 is formed a semi-circular slot 14 which is symmetrical with reference to the vertical plane containing the middle projections 5—5' of the two tubes 1—2; in this plane is disposed a stop 15 which is mounted on the plates 10 and extends through said slot. In this latter are mounted two springs 16 which abut respectively against the stop 15 and one end of the slot, and thus the said springs will urge the tubes 1—2 into the middle position as shown, each time that the disk 9 is turned in one or the other direction, according to the arrows *x* or *y*.

B.—Switch operated at the end of the stroke.—Each of these switches consists of a straight glass tube 17 which is properly sealed and comprises two projections 18—19 or 18'—19' for the contact wires. The said tube may be turned about, and it contains mercury which may be used to join the said contact wires or may leave them separate, and for this purpose the frame 20 supporting the tube 17 is mounted on one side of a disk 21 which is rotatable in a bore formed in the main plate 22. In said bore is a notch 23 cooperating with an abutment stud 24 mounted on the periphery of the disk 21; in the lateral face of the said disk are formed two recesses 25 cooperating with a fastening member consisting of a ball 26 urged by a spring 27. The engagement of said ball in

one or the other recess, in combination with the stud 24, movable in the slot 23, determines the two positions which may be occupied by the disk 21.

- 5 The horizontal plane passing through the center of the ball 26 is preferably situated above the horizontal plane containing the axis of rotation of the disk 21, so that the spring 27 may produce a couple tending to complete 70
 10 the rotation of the disk 21 when it has cleared the middle position. The shaft of the disk turns in the back part of the bore in the main plate 22, which forms a cheek, and is provided with a lever 28 having two stops 29-30.
 15 Each stop may come upon the path of the movable carriage 31, and the switching tube 17 is thus stopped in one or the other of its oblique positions. The said bore in the plate 22 is closed by a cover.
 20 C.—*Electric outfit.*—The switches *b*—*b* are mounted on the respective sides of the guiding track of the movable carriage, so that the latter will engage with a switch when at the end of its movement. The reversing switch *a* 80
 25 is within reach of the operator.

One wire 33 of the supply circuit is connected to the fields 34 of the motor and leads to the middle projection 5' of the tube 2 of the reversing switch *a*. The other wire 34 of this 85
 30 circuit leads to the central projection 5 of the tube 1 of the said reversing switch *a*.

To one brush of the armature 35 is connected a wire 36 which is also connected to the projection 6' of the tube 2 and to the projection 18' of the switch *b*; the other projection 19' of the switch *b* is connected electrically to the projection 4 of the tube 1 of the reversing switch *a*.
 90

The other brush of the armature 35 is connected by the wire 37 to the projection 4' of the tube 2 of the reversing switch *a* and also to the projection 19' of the switch *b*, and the projection 18 of the switch *b* is connected to the projection 6 of the tube 1 of the reversing switch *a*.
 95

In Figure 1, the carriage 31 is supposed to be in the stationary position. The reversing switch *a* is in its middle position for breaking the circuit. The switches *b* used at the end of the motion have the circuit-closing positions as shown.
 100

When the carriage is to be displaced, the operator rocking the knob 9 to turn the reversing switch *a* in the direction of the arrow *x* or the arrow *y*, according to the direction in which the carriage is to be moved. One or the other of the switches 1—2 will thus close the circuit in the proper direction. When the knob is released, the tubes 1—2 are brought by the springs 16 into the circuit-breaking position, thus stopping the motor and the carriage or other movable device.
 105

If for any reason the carriage attains the end of its movement and the electric motor 110
 115 continues to operate, the carriage will meet

the corresponding stop 29, thus moving the lever 28; the switch tube 17 is accordingly operated, thus breaking the motor circuit. By acting upon the reversing switch *a* in order to bring back the carriage, the latter will place 75
 120 the switch *b* in its normal closing position, since it turns the corresponding lever by making contact with the stop 30.

I claim:

1. A switch comprising a support, a disk 125
 130 mounted on the support and having a concentric arcuate slot, a stop secured on the support and passing through said slot midway the ends thereof, expansion springs housed in said slot between the ends of the same and said stop, and a double mercury switch mounted concentrically upon the disk.
 135

2. A switch mechanism for controlling a movable object, said mechanism comprising a rockable disk, a mercury switch tube mounted on one side of the disk, and a lever member mounted on the opposite side of the disk and projecting radially beyond the disk and having its outer end provided with spaced shoulders extending into the path of the 90
 140 movable object.
 145

3. A switch mechanism for controlling a movable object, said mechanism comprising a casing having a bore therethrough and provided with a circumferentially extending recess in the wall of the bore, a disk rotatably fitted in the bore of the casing, a projection on the edge of the disk playing in said recess, means in the casing engaging the periphery of the disk for yieldably holding the disk in a set position, a mercury switch tube mounted on one side of the disk, and a lever secured on the opposite side of the disk and projecting radially beyond the disk and provided on its outer end with spaced shoulders 100
 105 in the path of the movable object.
 110

In testimony whereof I affix my signature.
